UNITED STATES PATENT OFFICE.

WILLIAM R. DELANEY, OF NEW YORK, N. Y., ASSIGNOR TO BRICK & BALLERSTEIN, OF NEW YORK, N. Y., A COPARTNERSHIP.

MILLINERY BOX.

Application filed May 11, 1923. Serial No. 638,421.

To all whom it may concern:

Be it known that I, WILLIAM R. DELANEY, a citizen of the United States, and a resident of the city, county, and State of New York, have invented certain new and useful improvements in Millinery Boxes, set forth in the following specification.

This invention relates to lidded boxes of the type constructed of a cheap material such as paper board, straw board, cardboard and the like. It applies particularly to millinery boxes sometimes known as band boxes.

The object of the invention is to cause a mechanical cooperative functioning between a completely encircling flange provided on a lid and the open top body portion of a box of this construction in such a way that when the lid is hinged to the body portion, an automatic tucking in or seating function of the body portion into the flange of the lid takes place and also so that when the lid is closed that the box structure will have imparted to it considerable reinforcing action by the lid.

Heretofore, it has been customary to form boxes of this character with lids hinged to the upper margin of the box body and with the lid provided with a discontinuous flange. With such construction, the stresses have been directly applicable to the hinge between the lid and the body, and the heels of the lid flange have had an inherent tendency, instead of overlying the walls of the body portion, to force themselves against the inside faces of the walls of the body portion or to catch on the tops of the margin of these walls.

A particular object of the invention is to overcome this tendency when employing a lid hinged to a box body constructed of this fragile sheet material.

The above and further objects of the invention will better be understood by reference to the single embodiment of my invention, which is described in the following specification in connection with the accompanying drawing solely for purposes of illustration and not for limitations.

In the drawings, like characters designate corresponding parts in the several figures of which Fig. 1 is a perspective view showing the preferred embodiment of my invention for millinery boxes.

Fig. 2 is a rear perspective drawn to a small scale of the same construction.

Fig. 3 is a longitudinal vertical section, parts broken away, of my preferred construction, and

Fig. 4 is a perspective view with parts broken away, showing the lid and flange function, which it is an object of my invention to overcome.

With a box A of paper board construction such as that indicated in Fig. 4, undesirable functioning tendencies are present. In this construction, a flat rear wall 1 has hinged to its upper margin 2 a lid 3. The lid 3 is provided with a discontinuous flange 4. In closing this lid 3 upon the body portion 5 of the box A, the heels 6 and 7 of the flange 4, which should occupy a position outside of the walls 8 and 9, have a tendency to jump inside of the walls 8 and 9. In fact, with a box of this horizontal contour, these heels 6 and 7 have more than a tendency to do this. They always do it; but the tendency is present even in boxes in which the walls 8 and 9 are at right angles to the flat rear wall 1. Obviously, as lid 3 is pressed down home upon the body portion 5 with the heels 6 and 7 of the flange 4 starting out inside of the walls 8 and 9, there comes a position at which all of the flange 4 cannot tuck inside of the body portion. As a result, the lid does not close.

It is necessary, with the fingers, to bend out the heels 6 and 7 so that they start in with the closing of the lid straddling or lying outside of the walls 8 and 9. In fact, it is necessary, often, to tuck in the rim 10 of the body portion 5 at various places before the lid can be closed. With a box of this construction, with the lid closed bending stresses concentrate on the hinged line 2, which constitutes a line of sheer, soon breaking the hinge loose.

With my improved construction, I employ an open top body portion of any suitable construction of cardboard, straw board or paste board or the like, the walls of which include a flat vertical rear wall 11, a bottom wall 12, which extends out on rightangles to the rear wall and sidewalls 13 and 14, which, in the embodiment illustrated, extend out from the vertical margins of the rear wall 11, first outwardly flaring and then curving inwardly to form a com-

plete enclosure for the body portion B, being secured at their bottom edges to the margin of the bottom wall 12. I desire, however, that it be understood that I do not limit myself to this curvilinear configuration for the sidewalls 13 and 14. The upper margin 15 of the sidewalls 13 and 14 and 16 of the rear wall 11 terminate in the same horizontal plane.

10 A lid or cover C is formed with a top wall 17 corresponding preferably to the outer horizontal configuration of the side and rear walls and its margin is bound with a right-angularly positioned pendant continuous flange 18, the rear wall 19 of which is flat, adapted to overly the top portion of the rear wall 11 and outside thereof. A hinge 20 secures this flat portion 19 flexibly to the rear wall 11 at a distance below the top margin 20 of the rear wall equal to the depth of the flange 19. In the construction illustrated, the rear wall 11 is shown provided with a reinforcing or overlying wall 21 which causes this rear wall to be of double thickness below the flange 19 and it is, preferably, to this reinforcing wall 21 that the hinge 20 is secured. It is to be understood that the entire cardboard structure of this box may be covered with finishing material, such as 30 ornamental paper 22, 23 and 24.

Stop straps 25 and 26 are preferably interconnected between the sidewalls 13 and 14 and the lid C to limit its outward swing. A tape or ribbon 30 is fixed to the lip of the lid C farthest from the hinge and a corresponding tape 31 is fixed to the body portion B, so that the two tapes may be tied together to hold the lid closed. The carrying bail 32 is also preferably secured to the box body 40 portion B by passing through suitable slits in the walls thereof and by further attachment to the walls as may be necessary.

It should be noted that the hinge of the lid C to the body portion B is indirect; that 45 the hinging is between the bottom margin 33 of flange 19 and the top margin of reinforcing wall 21, so that the flange 18, even with the lid open as shown in Figures 1 and 2 from its very commencement at the locality 50 of the hinge 20, straddles with its portions 35 and 36 and lies against the outside face of the sidewalls 13 and 14. Its positioning is such that it cannot enter against the inner face of these sidewalls. In fact, the corners 55 37 and 38 operate somewhat as cams against

these portions 35 and 36, automatically causing the flange 18 to seat conveniently and readily outside of the walls of the body portion. This is accomplished without any manual manipulation of the flange or edges 60 of the walls and serves greatly to preserve unbroken integrity of the box as a whole.

This arrangement also enables the lid to fit snuggly about the open mouth of the body portion so that its continuous flange aids in 65 reinforcing the wall. Stresses in the locality of the hinged rear portion are also distributed partly between the locality of the hinge itself and between the upper margin 70 16 of the rear wall where it contacts with the top wall 17 of the lid.

The inventive thought may have a variety of expressions, as is contemplated in what I claim and desire to secure by United States Letters Patent:

A self-stiffened combination of band-box with a lid comprising an open-top body portion, the walls of which are somewhat resilient and are comprised of paper-board and which walls include a flat rear wall, a bottom wall and side-walls bulging outwardly from said flat rear wall and extending substantially vertically upwardly from the rim of said bottom wall and so that the top rim of said rear wall and bulging side walls are 80 continuous one into the other, and are bounded by the same horizontal plane; a lid for said body, also composed of paper-board and consisting of a top-wall of a configuration corresponding to the outer circumference of said rear and side-walls and a continuous flange pendant at right angles from said top-wall and having a flat rear portion to fit against said flat rear wall and a bulging portion to fit about the said bulging portion of said side-walls, the depth of said flange and the bulging of said side-walls being such that a mutual camming action and a mutual yielding commence with the closing of said lid from a relatively open position and continues throughout substantially all of the closing action to effect the automatic seating of all said flange snugly about said side and rear walls in response to a hinged movement of said lid.

In witness whereof, I have signed my name to this specification this 8th day of May, 1923.

WILLIAM R. DELANEY.
